UNITED STATES PATENT OFFICE.

OTTO J. HAARLANDER, OF SOUTH ORANGE, NEW JERSEY, ASSIGNOR TO NEW JERSEY
PATENT COMPANY, OF WEST ORANGE, NEW JERSEY, A CORPORATION OF NEW JERSEY.

DESIGN FOR A PHONOGRAPH CABINET.

Application filed October 25, 1922. Serial No. 4,093. Term of patent 14 years.

To all whom it may concern:

Be it known that I, OTTO J. HAARLANDER, a citizen of the United States, residing in South Orange, county of Essex, and State of New Jersey, have invented a new, original, and ornamental Design for Phonograph Cabinets, of which the following is a specification, reference being had to the accompanying drawing, forming a part thereof.

The figure is a perspective view of a phonograph cabinet showing my new design.

I claim:

The ornamental design for a phonograph cabinet as shown.

OTTO J. HAARLANDER.
